UNITED STATES PATENT OFFICE.

THOMAS N. JORDAN, JR., OF MOBILE, ALABAMA.

ADJUSTABLE-TENSION SAW-GAGE.

1,258,575.

Specification of Letters Patent.

Patented Mar. 5, 1918.

Application filed February 24, 1917. Serial No. 150,726.

To all whom it may concern:

Be it known that I, THOMAS N. JORDAN, Jr., a citizen of the United States, and a resident of Mobile, in the county of Mobile and State of Alabama, have invented a certain new and useful Improvement in Adjustable-Tension Saw-Gages, of which the following is a specification.

My present invention relates generally to saw gages, and particularly to one adapted for use both as a straight edge, in connection with bandsaws to detect the effect of unequal tension therealong, and as an adjustable tension gage for dished circular saws, my object being to provide a simple, strong, and effective device of this character, adjustment of which may be readily and quickly made.

The preferred means by which the above objects are carried out, are shown in the accompanying drawing, forming a part of this specification, and wherein—

Figure 1 is a side elevation of my improved gage.

Fig. 2 is vertical longitudinal section illustrating parts in normal position.

Fig. 3 is a similar view illustrating deflection of the gage bar.

Fig. 4 is an enlargement of the central portion of Fig. 3, illustrating practical application of the device to a circular saw, and

Figs. 5, 6, and 7 are vertical cross sections taken respectively on lines 5—5, 6—6, and 7—7 of Fig. 4.

Referring now to these figures, my invention comprises a pair of spaced parallel side bars 10 and 11 having straight lower edges 12 and beveled upper edges 13, the latter being inclined from a substantially central point at which the side plates 10 and 11 are connected in spaced apart relation by filler plates 14 and 15, said side plates 10 and 11 having aligned openings 16 elongated in the direction of their longitudinal axes and located at a substantially central point, and the inner ends of the said filler plates being cut away adjacent said opening 16 and as particularly seen at 17 in Figs. 2, 3, and 4.

The side plates 10 and 11 and the filler plates 14 and 15 are riveted or otherwise suitably secured together by fastening members at 18, so that the side plates are rigidly braced in their spaced relation, the filler plates 14 and 15 being themselves spaced apart in a direction longitudinally of the side plates 10 and 11 in order to form a

transverse guide channel, for a purpose to be hereinafter described.

Between the straight edges 12 of the side plates 10 and 11, is disposed a longitudinal 60 gage or deflection bar 19, the outer normally straight edge of which extends outwardly beyond, and normally parallel with, the straight edges 12 of the side plates 10 and 11, and the said bar 19 being provided with 65 openings adjacent its extremities by which it is connected to the extremities of the side plates 10 and 11 through the use of suitable fastening members shown at 20 such as rivets extending through the deflection bar. 70

Thus the bar 19 being free of connection except at its ends, is capable of deflection to produce a desired curvature at its outer edge for gaging the curvature of a dished circular saw, such as indicated at A in Fig. 75 4, by means of an adjusting member 21 slidably movable between the side plates 10 and 11 and generally flat for this purpose, the upper portion of the said member being disposed in the guide channel formed between the spaced filler plates 14 and 15 and having its upper end provided with graduations at 22 adjacent the upper edge of the said side plates, the lower ends of said adjusting member 21 extending into engagement with the upper or inner edge of the deflection bar 19 at a point intermediate the secured ends of the latter. 80

The adjusting member 21 is also provided with an enlarged threaded portion 23 intermediate its ends extending into the openings 16 of the side plates and there engaged by an adjusting nut 24 also extending within the said openings whereby the member 21 may be adjusted transversely of the gage by 85 rotation of the said nut, the latter having bearing against the edges of the side plates 10 and 11 and the filler plates 14 and 15 at one side of the openings 16. 95

It will thus be seen that the parts of my 100 improved gage while retaining the desired flexibility for adjusting purposes, are otherwise strong, rigid, and durable, and that the gage as a whole is capable of ready and quick adjustment, and effective action, in 105 connection with the use to which it is designed.

I claim:

1. An adjustable tension saw gage comprising a pair of spaced side plates having 110 openings elongated in the direction of their longitudinal axes and located substantially

centrally thereof, a deflection bar connected at its extremities to the extremities of said side plates and disposed between the lower portions of said plates, with its outer edge 5 projecting beyond and normally parallel with, the adjacent plate edges, filler plates rigidly connecting the said side plates intermediate the ends of the latter and spaced from one another longitudinally of the side 10 plates to form a transverse guide channel, a flat adjusting member slidable between said side plates in the channel between said filler plates and having an enlarged threaded portion within the said openings, and a 15 nut engaging the said threaded portion of said adjusting member and also disposed in the said openings for bearing against portions of the side plates and filler plates at one side of the opening.

20 2. An adjustable tension saw gage comprising a pair of spaced side plates having openings elongated in the direction of their longitudinal axes and located substantially centrally thereof, a deflection bar connected 25 at its extremities to the extremities of said side plates and disposed between the lower portions of said plates, with its outer edge projecting beyond and normally parallel with, the adjacent plate edges, filler plates 30 rigidly connecting the said side plates intermediate the ends of the latter and spaced from one another longitudinally of the side plates to form a transverse guide channel,

a flat adjusting member slidable between said side plates in the channel between said filler plates and having an enlarged threaded portion within the said openings, and a nut 35 engaging the said threaded portion of said adjusting member and also disposed in the said openings for bearing against portions of the side plates and filler plates at one side of the opening, said adjusting member being also provided at its upper end with graduations adjacent the opposite edges of the 40 said side plates, for the purpose described. 45

3. An adjustable tension saw gage comprising a pair of spaced apart side plates having intermediate openings, a deflection bar disposed between the said side plates along one edge thereof and connected at its opposite ends thereto, an adjusting member 50 slidably movable between the said side plates transversely thereof with its inner end in engagement with the inner edge of the said deflection bar intermediate the ends of the latter, said adjusting member having its opposite end projecting beyond the opposite edges of the side plates and provided with 55 graduations for the purpose described, and an adjusting member disposed in the openings of the side plates and engaging the said 60 adjusting member for adjusting the latter.

THOMAS N. JORDAN, JR.
